UNITED STATES PATENT OFFICE.

OTTO SPAHR AND CHARLES STICHLER, OF PHILADELPHIA, PENNSYLVANIA.

DESIGN FOR A SAD-IRON.

42,443.

Specification for Design.

Patented Apr. 30, 1912.

Application filed November 22, 1911. Serial No. 661,869. Term of patent 14 years.

To all whom it may concern:

Be it known that we, OTTO SPAHR and CHARLES STICHLER, the former a citizen of the United States and the latter a subject of the Emperor of Germany, and both residents of Philadelphia, county of Philadelphia, State of Pennsylvania, have jointly invented a new, original, and ornamental Design for a Sad-Iron, of which the following is a specification.

Reference is to be had to the accompanying drawings in which—

Figure 1 is a side elevation of a sad iron embodying our new design; Fig. 2 is a plan view thereof and Fig. 3 is an end elevation of the same.

The design comprises a body having substantially a triangular shape in plan view with curved side walls and a substantially straight end wall. The side walls are partly cut away to form depressions *a* while the end wall is cut away to form two depres-

sions *b*. A number of circles *c* are arranged lengthwise of the side walls near the base thereof and a tube *d* projects from the end wall and extends at an angle to the vertical and is provided with an ornamental head *e*, on which appear a number of circles *f*. A tail-like projection *g* at the rear of the iron and a handle *h* supported by means of a substantially U-shaped continuous carrier form part of the design.

The complete design comprises a sad iron of pleasing form and ornamental appearance.

We claim—

The ornamental design for a sad iron as shown and described.

OTTO SPAHR.
CHARLES STICHLER.
